(57) **CLAIM**

The ornamental design for a pipe for fluid distribution, as shown and described.

DESCRIPTION

FIG. 1 is a front, top, right side perspective view of a pipe for fluid distribution, in accordance with the present invention;

FIG. 2 is a rear, bottom, left side perspective view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines represent portions of the pipe for fluid distribution that form no part of the claimed design. The long dash short dash long dash broken lines shown in the drawings depict boundaries of the claim and form no part thereof.

1 Claim, 8 Drawing Sheets
